UNITED STATES PATENT OFFICE.

BENJAMIN T. WENDELL, OF BOSTON, MASSACHUSETTS.

DESIGN FOR A BASE-PLATE FOR GARMENT-CLASPS.

No. 39,237.

Specification for Design.

Patented March 31, 1908.

Application filed December 6, 1907. Serial No. 405,452. Term of patent 14 years.

To all whom it may concern:

Be it known that I, BENJAMIN T. WENDELL, a citizen of the United States, residing at Boston, county of Suffolk, State of Massachusetts, have invented a new, original, and ornamental Design for a Base-Plate for Garment-Clasps, of which the following is a specification, reference being had to the accompanying drawing, forming part thereof.

Figure 1 is a top plan view, and Fig. 2 is a

bottom plan view, of a base plate for garment clasps, showing my new design.

I claim:

The ornamental design for a base plate for garment clasps as shown.

BENJAMIN T. WENDELL.

Witnesses:

ROGER S. WARNER,
JOHN C. EDWARDS.
